UNITED STATES PATENT OFFICE.

CLIFFORD G. KING, OF PROVIDENCE, RHODE ISLAND, ASSIGNOR TO HIMSELF, AND
ARTHUR I. CLARK, OF CRANSTON, RHODE ISLAND.

BRACELET.

1,303,220.

Specification of Letters Patent.

Patented May 6, 1919.

Application filed June 8, 1918. Serial No. 238,821.

To all whom it may concern:

Be it known that I, CLIFFORD G. KING, a citizen of the United States, and a resident of Providence, in the county of Providence and State of Rhode Island, have invented 5 a new and useful Improvement in Bracelets, of which the following is a specification.

The present invention which is an improvement on the expansible bracelet described in my Patent No. 1,264,810 dated April 30, 1918 has for its object the improvement and simplification of the member which hingedly connects the tubes and shells which make up the bracelet.

15 An illustrative embodiment of my invention is shown in the accompanying drawings in which—

Figure 1 is a vertical longitudinal section showing the parts in their normal position.

20 Fig. 2 is a similar section showing the parts in expanded position. Fig. 3 is a horizontal longitudinal section showing the parts in normal position. Fig. 4 is a horizontal section showing the parts in extended position.

25 Fig. 5 is a perspective view of one of the outer shell members. Fig. 6 is a perspective view of one of the inner tube members. Fig. 7 is a plan view of one of the connecting members. Fig. 8 is a section taken on 30 the line 8—8 of Fig. 7. Fig. 9 is a perspective view of the key which coöperates with the connecting member. Fig. 10 is an elevation of the bracelet complete. Fig. 11 is an elevation of one form of catch that may

35 be used for securing the bracelet to a watch. Fig. 12 is a section taken on the line 12—12 of Fig. 11. Fig. 13 is a horizontal section of the latching device taken on the line 13—13 of Fig. 10.

40 In the particular drawings selected for more fully disclosing my invention 20 represents an outer shell and 21 an inner tube, the inwardly bent concave ends 22 of the shell coöperating with the inwardly bent 45 convex ends 23 of the tube to form a hinged joint, the members of which are connected by the member 24 which consists of a bifurcated plate of spring material the end of each arm of which is provided with a recess 50 25 adapted to engage the said inwardly bent ends of a tube and shell.

55 A spiral spring 26 surrounds the connecting member 24 and is retained in position by the lateral projections 27 on one end of the connecting member, said projections be-

ing bent outwardly after said member has been inserted through the spring. The connecting member with its surrounding spring is inserted in the tube through the open end thereof and the lips 28 are then bent inwardly so that they rest against the forward end of the spring. A key 29 having a lateral head 30 provided with two parallel longitudinal extensions 31 is placed in the space between the forward ends of the arms 60 of the connecting member so that it lies in front of the central finger 32 of the latter. The tube with its inclosed connecting member and key is inserted through the open end of a shell. By means of a pin the key is 65 now raised and the arms of the connecting member pressed together so that one arm lies over the finger 32 and the other under the same, the juxtaposed edges of said arms and finger being rounded to facilitate this 70 operation. The head of the connecting member may now be drawn out of the forward end of the shell and the inwardly bent ends 23 of a tube inserted in the recesses 25, whereupon the arms of the connecting member 75 will snap over the inwardly bent ends of both tube and shell, and the key 29 will fall back in position so as to maintain the engagement of the connecting member with said ends.

80 Secured to each end tube of the bracelet is a catch consisting of a body portion 33 terminating in a hook 34 for engagement with the rings of a wrist watch 35. The tongue 36 which is pivoted in said body portion of the catch preferably has its sides provided with enlargements 37 arranged to co-operate the similarly shaped depressions in the walls of the catch, so as to hold the tongue in closed position. The outer shell 85 inclosing the end tube to which the catch is secured acts as a safety lock for the catch, as the tongue cannot be moved until said shell is drawn away from the tongue.

90 It is desirable to provide watch bracelets with means for opening and closing the same at a point intermediate the ends thereof which are coupled to the watch so that said ends need not ever be uncoupled. For this purpose I have shown a latching device comprising the shell 38 provided with two pairs of oppositely arranged perforations 39 near one end thereof and having the convex hinge member 40 soldered to the other end thereof, said member being connected with the juxta- 100 105 110

posed concave member of the adjacent shell 20, together with a coöperating tube 41, the end of which is hingedly connected to the concave hinge member of the shell 20 which 5 is adjacent thereto. The said tube 41 is provided with two pairs of oppositely arranged perforations 42 near one end thereof which register respectively with the perforations 39 in the shell. The latch consists as shown 10 of two arms each provided with a finger piece 43 arranged to project through one pair of perforations in said tube and shell and with a lug 44 arranged to project through the other pair of perforations in 15 the tube and to take into the other pair of perforations in said shell, thereby to latch the said shell and tube together. Preferably spring means are provided for forcing the arms of the latch outwardly, and in the 20 present instance I have shown said arms secured to or formed integral with a spiral spring 45. As will be obvious when the finger pieces 43 are pressed inwardly the lugs 44 will clear the shell 38 so that the 25 tube may be withdrawn from said shell.

While for the purpose of more fully disclosing a particular embodiment of my invention I have specifically described the same, it will be understood that various 30 modifications may be made without departing from my invention as defined by the appended claims.

I claim:

1. A bracelet comprising in combination 35 a tube and a shell each having its walls at its juxtaposed ends bent inwardly, and a connecting member in said shell, said member consisting of a bifurcated plate of spring material, the end of each arm of which is provided with a recess adapted to engage the 40 said inwardly bent ends of said tube and shell.

2. A bracelet comprising in combination 45 a tube and a shell each having its walls at its juxtaposed ends bent inwardly, a connecting member in said shell, said member consisting of a bifurcated plate of spring material, the end of each arm of which is provided with a recess adapted to engage the 50 said inwardly bent ends of said tube and shell, a tube inclosed within said shell and inclosing said connecting member, and a spring surrounding said connecting member, one end of the last mentioned tube having a 55 lug coöperating with one end of said spring

and said connecting member being provided with a lug coöperating with the other end of said spring.

3. A bracelet comprising in combination 60 a tube and a shell each having its walls at its juxtaposed ends bent inwardly, a connecting member in said shell, said member consisting of a bifurcated plate of spring material, the end of each arm of which is provided with a recess adapted to engage 65 the said inwardly bent ends of said tube and shell, and means for maintaining the engagement between said arms and said inwardly bent ends.

4. A bracelet comprising in combination 70 a tube and a shell each having its walls at its juxtaposed ends bent inwardly, a connecting member in said shell, said member consisting of a bifurcated plate of spring material, the end of each arm of which is provided with a recess adapted to engage the 75 said inwardly bent ends of said tube and shell, and a key arranged to fit into the space between the ends of said arms.

5. A bracelet comprising in combination 80 a tube and a shell each having its walls at its juxtaposed ends bent inwardly, a connecting member in said shell, said member consisting of a bifurcated plate of spring material, the end of each arm of which is provided with a recess adapted to engage the 85 said inwardly bent ends of said tube and shell, and a key arranged to fit into the space between the ends of said arms, said key having a laterally extending head terminating in two parallel longitudinal extensions each lying alongside one of said arms. 90

6. A bracelet comprising in combination 95 a tube and a shell each having its walls at its juxtaposed ends bent inwardly, a connecting member in said shell, said member consisting of a bifurcated plate of spring material, the end of each arm of which is provided with a recess adapted to engage the 100 said inwardly bent ends of said tube and shell, and having a central finger terminating short of the end thereof, and a key arranged to fit into the space between the ends of said arms and lying forward of the end of said finger. 105

In testimony whereof, I have hereunto subscribed my name this 28th day of May, 1918.

CLIFFORD G. KING.
